UNITED STATES PATENT OFFICE.

JOHN H. STRAIN, OF BOSTON, MASSACHUSETTS.

DESIGN FOR A FOOT-PROPELLED CHILD'S CAR.

56,204.

Specification for Design. Patented Aug. 24, 1920.

Application filed May 5, 1920. Serial No. 379,141. Term of patent 7 years.

To all whom it may concern:

Be it known that I, JOHN H. STRAIN, a citizen of the United States, residing at Boston, in the county of Suffolk and State of Massachusetts, have invented a new, original, and ornamental Design for a Foot-Propelled Child's Car, of which the following is a specification, reference being had to the accompanying drawing, forming a part thereof.

In the drawing,

Figure 1 is a plan view of the car,

Fig. 2 is a side elevation of the same, and Fig. 3 is an end view.

I claim,—

The ornamental design for a foot propelled child's car as herein shown.

JOHN H. STRAIN.
